UNITED STATES PATENT OFFICE.

JOSEPH G. STADELMAN, OF CHICAGO, ILLINOIS.

ROOF-TRUSS CONSTRUCTION.

1,277,766.

Specification of Letters Patent. Patented Sept. 3, 1918.

Application filed October 29, 1917. Serial No. 199,208.

To all whom it may concern:

Be it known that I, JOSEPH G. STADELMAN, a citizen of the United States, residing at Chicago, in the county of Cook and State 5 of Illinois, have invented a certain new and useful Improvement in Roof-Truss Construction, of which the following is a full, clear, concise, and exact description, reference being had to the accompanying drawings, forming a part of this specification.

My improved truss is particularly intended for use in portable or sectional buildings, such as are illustrated in my copending applications Serial Nos. 85,825 filed March 15 25, 1916, and 176,468 filed June 23, 1917.

The truss members illustrated in these applications were secured to the wall plates of the building by providing both the truss member and the wall plate with bonding 20 notches, which were adapted to interlock the truss members to the wall plates.

This construction has the advantage of quick assemblage and disassemblage of these parts which is very important in a portable 25 house where facility and rapidity of erection are essential, but the operation of cutting the notch in the truss member was quite laborious and weakened the truss considerably. The wall plate has no large stresses 30 to resist, and can well withstand such notching but the notch in the truss member occurred directly at the point of support of the truss, and resulted in a weakness where the shearing force was largest.

In the present embodiment I dispense with the notch in the truss member and obtain a stronger truss with a saving of labor, without sacrificing the facility of assembly and disassembly inherent in the former method. 35 This is fully explained in the following specification, taken in connection with the accompanying drawing, in which—

Figure 1 is a fragmentary elevational view of my improved roof truss;

Fig. 2 is a fragmentary perspective view of the roof truss and wall plate in position for assembling;

Fig. 3 is an isolated perspective view of two of the blocks or bracket members; and

Fig. 4 is a fragmentary perspective view showing a modified roof truss.

The siding of the building comprises a plurality of panel sections 1, contiguously arranged along a suitable foundation. The 55 panel sections 1 consist of tongue and groove boards 2 extending vertically of the panel

sections, with transverse cross rails 3 serving to tie the boards together. A wall plate member 4 is arranged to seat astride the tops of the panel sections, a groove 5 therein receiving the tops of the siding boards, the inner beam 6 of the wall plate member resting upon the upper cross rails 3 of the contiguous panel sections 1. The wall plate member 4 is secured to the panel sections 1 by either bolts or nails 7. The present invention is not directly concerned with the erection of the siding panels and wall plates and for a detailed description thereof, attention is directed to the applications previously referred to.

The truss member designated 10 in its entirety, comprises a tie-beam 11, the king posts 12, the inclined rafters 13, and the truss plates 14. The tie-beam extends from 75 side to side of the house for bracing the walls and for supporting the king posts 12. The latter are nailed upon the sides of the tie-beam 11 and rafters 13 as are the reinforcing truss plates 14. The rafter 13 inclines downwardly and is secured by bolts 15 or by nails to the oblique edge of the tie-beam 11. The heads of the bolts 15 are countersunk in the rafter 13 to afford a smooth upper surface for supporting the 85 roof panels 16.

The wall plate member 4 is provided with oblique notches 17 for the reception of the inclined rafter 13, shown in superposed relation in Fig. 2. The notch 17 is cut very 90 shallow, its only function being to prevent lateral movement of the roof truss 10. The tie-beam 11 has a squared shoulder portion 11' projecting slightly below the rafter 13 and this shoulder portion forms an abutment bearing against the inner face of the wall plate member 4 to prevent inward collapse of the siding or to prevent movement of the roof truss in that direction. The rafter 13 extends out beyond the wall plate 100 member 4 and supports roof sections 16 which form eaves on the building. To the underside of the extending portion of the rafter 13 is secured a block or bracket member 18 which forms an abutment for engaging the outer face of the wall plate member 4 for preventing outward collapse of the siding 1 or movement of the roof truss. The block or bracket member 18 is preferably given an ornamental configuration to enhance the appearance of the eaves.

The shoulder 11' of the tie-beam 11 and

the block 18 constitute a "built-up" notch and perform the same function that the bonding notch did in my previous trusses, but do not weaken the truss.

5 A wrought iron strap 20 is bolted to the cross rails 3, the wall plate member 4 and to the rafter 13 to tie the truss 10 to the siding of the building. This is the preferred means of connection between the roof 10 and siding, though other suitable connecting means may be employed.

In the modification illustrated in Fig. 4, two parallel rafters 21-21 are employed. At the ridge of the truss the rafters 21-21 15 are fastened upon opposite sides of a single king post, not shown, and at the eaves of the truss the rafters are fastened upon opposite sides of the tie-beam 11. The tie-beam 11 has the projecting shoulder 11', similar to 20 the construction of Fig. 1.

The oblique notch 17 is made considerably wider for the reception of both rafters 21-21. In this embodiment the block or bracket member 18 comprises either a single 25 block of a breadth sufficient to span both rafters 21-21 (Fig. 4), or comprises two narrow blocks 18-18, (Fig. 3) to be secured under individual rafters 21-21.

In Fig. 2 I have made a fragmentary 30 showing of the roof panels 16. These panels are provided with cross rails 24, the cross rails of contiguous panels lying upon opposite sides of the rafter 13 and being secured thereto by bolts passing through both rails 35 and the rafter. The rails 24 are set back from the edges of the roof panels 16, leaving a margin of panel overlying the rafter 13.

The roof panels for use in connection 40 with the modified truss illustrated in Fig. 4 are illustrated in my co-pending application Serial Number 85,825, filed March 22nd, 1916.

The outer board 25 of the wall plate member 4 extends up into engagement with the roof panels 16, as shown in dotted lines in 45 Fig. 1, and closes off the space between the roof panels and wall plate.

From the foregoing it will be apparent that the erection of my improved truss can be accomplished with ease and rapidity, and when once in place it is securely held against movement in any direction.

The oblique notch 17 prevents lateral movement of the truss, the shoulder 11' and the bracket member 18 prevent longitudinal 55 movement of the truss, and the strap 20 prevents vertical lifting of the truss under the action of a high wind.

Other modifications will immediately appear to those skilled in the art, but I intend 60 these to come within the spirit and scope of the appended claim.

What I claim is:

A portable building construction comprising 65 a roof truss constructed of rafters of substantially uniform depth, approximately the least necessary to support the stress, wall plates upon which the rafters rest, the lower ends of the rafters projecting beyond the wall plates to form an eave, a tie beam connecting said rafters, its ends providing shoulders to abut the inner sides of the wall plates, the wall plates having inclined bottomed notches to receive the rafters in uncut condition, and finishing blocks for the outer 70 ends of the rafters secured to the under sides of the projecting ends thereof, the inner ends of said blocks providing abutting shoulders opposed to the ends of the tie beam to engage the outer sides of said 75 plates.

In witness whereof, I hereunto subscribe my name this 26 day of October, A. D. 1917.

JOSEPH G. STADELMAN.
